UNITED STATES PATENT OFFICE

GARTH G. GILPIN, OF RIVERSIDE, ILLINOIS, ASSIGNOR TO UNION METAL PRODUCTS COMPANY, OF CHICAGO, ILLINOIS, A CORPORATION OF DELAWARE

CAST HOPPER DOOR

Application filed January 27, 1928. Serial No. 250,003.

My invention relates to the construction of railway cars having drop doors, such as hopper cars, hopper gondola cars, drop-bottom or general service gondola cars, mill type gondolas, having drop end doors, or the like, having a door forming a part of the car for retaining the load therein, which door is provided with hinges adjacent one of its edges and is capable of being "dropped" or swung open. Any means of raising the door to the closed position and any means for locking and releasing the door may be employed with my device.

A door for this purpose must be very strong and durable because:

First, it is a part of the floor of the car and as such must sustain the load as well as the impact blow of the load when the car is in motion. Second, the car is frequently loaded from chutes or tipplers from a height of ten feet or more, causing the load to be dropped directly upon the doors. Third, clam shell buckets are frequently used to unload such cars and it is not uncommon for these buckets to rest upon and drag over the doors. Fourth, when the door suddenly comes to rest after being dropped, it is not only subjected to a severe shock but it must sustain the severe impact thrust of the load which of course follows the door. Fifth, as the load is theoretically equally distributed, the door must be strong over its entire area and must be capable of transmitting the resulting stresses to the car body without much deflection and no substantial distortion. Any bending of the door or drooping of the corners would cause a leak of the lading, especially of such fine material as sand, chats, etc. Any bending or warping might interfere with the complete closing and locking of the door.

An object of the invention is to provide a door of cast metal, preferably malleable iron or cast steel, having a panel portion forming a floor or wall of a car and to reinforce such panel with cast integral members and to form and shape the entire door so that it will not be deformed by warping when cooling, and furthermore, will eliminate shrinkage cracks and internal stresses.

Both cast metal and annealed cast metal offer greater resistance to corrosion (and similar chemical actions) than rolled steel owing to the texture of the metal. When rolled steel is deformed between dies (whether heated or not) the fibres on the tension side of the metal are opened up or separated by stretching, while the fibres on the compression side of the metal are forced together and upset. Both such opening up and upsetting actions disrupts the homogeneity of the fibres, thus permitting the entrance of moisture therebetween and augmenting corrosion, therefore, another object is to provide a door more capable to resist corrosion. Railway cars are not only subject to the usual atmospheric conditions but are subject to chemical actions of certain loads, such as, for instance, wet coal which forms sulphuric acid.

In the drawings:

Fig. 1 shows a portion of a railway car with my device applied thereon.

Fig. 2 is a section on line 2—2 of Fig. 1.

Fig. 3 is a section on line 3—3 of Fig. 1.

Fig. 4 is a detail of the door from the underside.

Fig. 5 is a section on line 5—5 of Fig. 4.

Fig. 6 is a section on line 6—6 of Fig. 4.

Figs. 7 and 8 are modified forms of the invention.

In casting a door having an integral depending flange extending around all four of its sides, the liquid steel is preferably poured through a plurality of gates into the panel portion of the door from whence it flows into the integral flange. The lower portion of the flange, therefore, cools first and offers resistance to the contraction exerted by the cooling panel portion. If a transverse integral rib is provided which merges into opposite portions of the integral flange, the cooling of the panel portion would break one end (or may be both ends) of the transverse rib away from the integral flange or cause a rupture of the lower side of the transverse rib. These are called shrinkage cracks. The relatively cool perimeter of the panel (i. e., the integral flange) may offer sufficient resistance to the contraction of the cooling panel to crack the

panel. Sometimes these stresses are not sufficient to crack and sever the metal but cause internal (latent) stresses which when increased by a load imposed upon the door become sufficient to (and do) break the door.

To illustrate one adaptation of my device, I have shown a so-called "general service" drop bottom gondola car wherein the major portion of the floor consists of drop doors. The door openings are surrounded by the center construction 1, side wall 2 and cross diaphragms 3. In normal or closed position the door completely closes this opening and in fact is a trifle larger on all sides than the opening so as to provide a lap joint between the door and the car frame member. The doors are hinged to the center construction and are supported adjacent the side wall by the raising or locking mechanism. Any convenient stop may be used to limit the downward movement of the door.

The cast metal door comprises a panel 5 with a continuous depending integral flange 6 extending around all four sides of the panel.

The door is provided with a secondary rib 7 crossing each corner with its opposite ends merging into the depending flange 6 and a primary rib 8 connecting two of the secondary ribs which may be on the same side of the door, as shown in Fig. 4, or in diagonally opposite corners of the door, as shown in Fig. 8.

The door may further be strengthened by reinforcing ribs 9 extending parallel with the primary ribs 8, as shown in Fig. 4, or may extend angularly thereto, as shown in Fig. 7.

In order to prevent shrinkage in cooling from breaking the reinforcing ribs away from their adjacent members I prefer to form them on curves or to wave them, or broadly speaking, to form them in some other than a straight line.

In Fig. 7 the arcuate secondary ribs 20 are connected by arcuate primary ribs 21 and by arcuate transverse reinforcing ribs 22.

In Fig. 8 the arcuate secondary ribs 30 merge into the primary arcuate reinforcing ribs 31, which in turn, merge together adjacent the middle portion of the door.

The hinge lugs 15 are cast integral with the depending flange 6 and some of the reinforcing ribs preferably terminate into the panel adjacent the integral hinge lugs so as to carry their stresses to the hinges.

The accompanying drawings illustrate the preferred form of the invention, though it is to be understood that the invention is not limited to the exact details of construction shown and described, as it is obvious that various modifications thereof within the scope of the claims will occur to persons skilled in the art.

In applications Serial No. 249,999; No. 65 250,000; No. 250,001 and No. 250,002, all

filed January 27, 1928, I have disclosed and claimed certain features disclosed but not claimed herein.

I claim:

1. A hinged door for a railway car consisting of an integral casting comprising a panel with a continuous flange adjacent its perimeter, a secondary rib crossing each corner with its opposite ends merging into the flange, and a primary rib connecting the secondary ribs on the same side of the door. 70

2. A hinged door for a railway car consisting of an integral casting comprising a panel with a continuous flange adjacent its perimeter, a secondary rib crossing each corner with its opposite ends merging into the flange, and a curved primary rib connecting the secondary ribs on the same side of the door. 80

3. A hinged door for a railway car consisting of an integral casting comprising a panel with a continuous flange adjacent its perimeter, a secondary rib crossing each corner with its opposite ends merging into the flange, and a primary rib connecting the secondary ribs on the same side of the door, and other ribs connecting said primary ribs. 90

4. A hinged door for a railway car consisting of an integral casting comprising a panel with a continuous flange adjacent its perimeter, a secondary rib crossing each corner with its opposite ends merging into the flange, a primary rib connecting the secondary ribs on the same side of the door, and another rib substantially parallel to the primary ribs. 95
